WIRE UNCOILING APPARATUS

Charles R. Rohweder, Belmont, Mass., assignor to
United Shoe Machinery Corporation, Flemington, N. J., a corporation of New Jersey

Application July 11, 1941, Serial No. 401,945

14 Claims. (Cl. 242—128)

This invention relates to wire uncoiling apparatus and more particularly to apparatus for utilizing wire in loosely wound coil form.

Wire after its manufacture is customarily formed into loosely wound coils the convolutions of which are laid more or less at random, with the result that the convolutions of each coil are not of uniform diameter nor are they all concentric to the axis of the coil. This renders it difficult to withdraw the wire from such coils because of the non-uniformity of the convolutions which are sometimes not easily separated from one another so that the wire kinks and otherwise interferes with the smooth operation of the mechanism employed in withdrawing the wire from the coil.

It is an object of the present invention to provide improved apparatus particularly adapted for use in facilitating the withdrawal of wire from loosely wound coils of the above-mentioned character. For the purpose in view, there is provided, in accordance with one feature of the invention, means which acts during the uncoiling of the wire to loosen each convolution of wire from the remainder of the coil, thus causing the wire to be withdrawn from the coil a single convolution at a time so that snarling or kinking of the wire is substantially avoided. This means, herein illustrated, comprises a rotatable take-off arm the inlet end of which is arranged to be vibrated by the action of the wire thereon in the uncoiling operation, the vibratory action of the inlet portion acting to loosen each convolution of the wire as it is uncoiled.

In another aspect, the invention provides a novel take-off arm having outlet and inlet portions relatively movable to accommodate the arm to varying widths and eccentricities of the convolutions of wire in coils formed in the manner above described. In the illustrated construction, the outlet and inlet portions of the take-off arm are connected by a flexible resilient portion which permits the inlet end portion to move relatively to the outlet portion in any direction transversely of the wire and by reason of its resiliency causes the inlet portion to vibrate in the uncoiling of the wire by reason of the action of the wire on the inlet portion.

The above and other features of the invention will now be more particularly described by reference to the accompanying drawings and pointed out in the claims.

In the drawing,

Fig. 1 is a plan view partly in section of one

form of apparatus in which the present invention may be embodied; and

Fig. 2 is an elevation partly in section of the apparatus shown in Fig. 1.

5 A coil of wire 10 is supported in a frame 12 which comprises a lower supporting plate 14 on which the coil of wire rests and a cover plate 16 for protecting the coil of wire from dirt, etc. The plates 14 and 16 are maintained in spaced relation by a circular wall 18 secured to and depending from the plate 16. Welded or otherwise secured to the interior of the wall 18 near its lower end is a plate 20 carrying pins 22 adapted to register with and pass through holes 24 in the lower plate 14 to facilitate assembly of the plates. A post 26 secured to the plate 20 and the top plate 16 extends upwardly and has a reduced portion 28 projecting above the top plate 16. The lower end of the post 26 is threaded to receive a nut 30 for securing the parts of the frame 12 together after a coil of wire has been placed therein. In placing a coil of wire in the frame, the plate 16 is inverted and the coil of wire placed thereon around the circular wall 18, after which the lower plate 14 is secured thereto by the nut 30 and the entire assemblage then turned right side up into the position shown in Fig. 2.

10 The wire-supporting frame 12 is supported in a base 32 which, as shown, comprises a pair of crossbars 34 and 36 provided with feet 38. Extending upwardly from the bars are posts 40 to the upper ends of which is secured a ring 42 thereby to form a rigid structure. The lower end of the post 26 below the threaded portion is reduced in diameter at 44 to fit into a hole formed at the intersections of the bars 34 and 36 thereby to determine the position of the frame 12 in the base 32.

15 The wire is drawn from the coil 10 through a rotatable, tubular take-off arm 46 which is secured at its upper end to a spindle 48. This spindle is journaled on the reduced upper end portion 28 of the post 26, and the lower end of the spindle is flanged at 49 and rests upon a boss 50 extending upwardly from the cover plate 16. To prevent upward movement of the spindle 48 relative to the post 26 a spring latch 52 secured to the boss 50 engages the upper surface of the flange 49. The take-off arm 46 extends downwardly and outwardly and has its lower end portion curved, as shown, to extend into the annular space formed between the ring 42 of the base and the cover plate 16. The lower end of the take-off arm is substantially concentric with the ring 42 and the coil of wire 10, as indicated clear-

ly in Fig. 1. As the wire is drawn from the coil 10 through the take-off arm 46 the take-off arm and the spindle 48 rotate about the axis of the post 26 by reason of the pull of the wire on the arm 46, thus causing the lower end portion of the arm to move in a circular path around the periphery of the coil 10.

For purposes of the present invention, the rotatable take-off arm 46 has its lower end portion or intake end made flexible and resilient so that it may accommodate itself to the varying widthwise and heightwise positions of the different convolutions of wire as they are uncoiled. The convolutions of the wire forming the coils for which this invention is particularly adapted are laid more or less at random so that the convolutions of each coil are not all concentric to the axis of the coil nor are they all of uniform diameter. As a result of this, the convolutions are sometimes not easily separated from one another, rendering it difficult to withdraw the wire from the coils. As illustrated herein, a coil spring 54 is formed at the intake end of the take-off arm which is yieldable in all directions relative to the take-off arm and will move horizontally, as indicated by the broken line positions of the spring in Fig. 1, from the normal position represented by full lines, in response to changes in the position of the wire widthwise of the coil as the wire is removed therefrom. Similarly, as the heightwise position of the wire relative to the coil varies, the spring will move, as indicated by the broken line positions in Fig. 2, from the normal heightwise position indicated by the full lines. By thus accommodating itself to sudden changes in the position of the wire as it enters the take-off arm, the spring avoids sharp bending of the wire at all times as the wire leaves the coil. The tension of the spring acts on the wire tending to separate each convolution of the wire as it is withdrawn, thus greatly facilitating its removal from the coil. The variations in the diameters of the convolutions of wire and their unsymmetrical disposition will cause substantially continuous movement of the spring 54 relative to the take-off arm 46 as the wire is withdrawn. As the spring moves out of its normal position, it will tend to return thereto by reason of its resiliency, which will cause the spring to vibrate very rapidly and shake the wire as it passes into the take-off arm. This shaking of the wire caused by the vibration of the spring assists in loosening each convolution of the wire from the remainder of the coil as the wire is withdrawn therefrom, thus reducing the tendency of lifting more than one convolution of the wire from the coil at any time. This prevents kinking of the wire and minimizes the load imposed on the mechanism which withdraws the wire from the coil, thereby greatly facilitating the uncoiling of the wire. To the outer end of the spring 54 is secured a short metal ring 56 which prevents wear between the wire and the outer end of the spring, thereby increasing the life of the apparatus. The arm 46 and the ring 56 thus constitute a take-off arm composed of relatively movable intake and outlet end portions to accommodate the arm to varying widths and eccentricities of the convolutions of wire in the coil. The spring 54 forms a flexible resilient connection between the inlet and outlet end portions permitting the inlet end to move in any direction transversely to the wire and to vibrate in response to the action of the wire thereon during the uncoiling operation.

This apparatus greatly facilitates uncoiling of

wire from the loosely wound coils by reducing the effort required in removing the wire from the coil. It also permits the use of such a coil with a machine to which it has heretofore been customary 5 to feed the wire from tightly wound reels. Inasmuch as the tightly wound reels are more expensive than the loosely wound coils this apparatus permits a reduction in the cost of operation of such machines. It will be apparent that the 10 take-off arm described above may be employed with other forms of wire-supporting apparatus than that disclosed herein.

Having thus described my invention, what I claim as new and desire to secure by Letters Patent of the United States is:

1. A wire uncoiling apparatus comprising a support for a coil of wire, a tubular take-off arm mounted to rotate about an axis substantially central of a coil of wire on the support, said take-off arm having a flexible resilient intake end, whereby said end is adapted to deviate from a circular path around the coil of wire in response to rotation of the take-off arm about said axis in the uncoiling operation.

2. A wire uncoiling apparatus comprising a support for a coil of wire, a tubular take-off arm mounted to rotate about an axis substantially central of a coil on the support, the lower end of said take-off arm being arranged to move around the coil of wire in response to rotation of the take-off arm in the uncoiling operation, and means at the intake end of said take-off arm arranged to be vibrated by the action of the wire thereon and thus to assist in loosening each convolution of the wire as it is uncoiled.

3. A wire uncoiling apparatus comprising a support for a coil of wire, a tubular take-off arm mounted to rotate about an axis substantially central of a coil on the support, the intake end of said take-off arm being arranged to move around the coil of wire in response to rotation of the take-off arm in the uncoiling operation, and a coil spring at the intake end of said take-off arm through which wire passes from said coil.

4. A wire uncoiling apparatus comprising a support for a coil of wire, a tubular take-off arm mounted to rotate about an axis substantially central of a coil on the support, the intake end of said take-off arm being arranged to move around the coil of wire in response to rotation of the take-off arm in the uncoiling operation, a coil spring at the intake end of said take-off arm through which wire passes from said coil, and a metallic ring at the outer end of said spring forming a wear-resisting surface over which the wire passes.

5. A wire uncoiling apparatus comprising a support for a coil of wire, a post secured to said support and rising centrally therefrom, a spindle journaled on said post, a take-off arm secured to the upper end of said spindle and extending downwardly and outwardly, the lower end of said take-off arm being arranged for movement around the coil of wire on the support in response to rotation of the take-off arm in the uncoiling operation, and a coil spring at the lower end of the take-off arm arranged to be vibrated by the action of the wire thereon and thus to assist in loosening each convolution of the wire as it is uncoiled.

6. A wire uncoiling apparatus comprising a support for a coil of wire, a post secured to said support and rising centrally therefrom, a spindle journaled on said post, a take-off arm secured to the upper end of said spindle and extending

downwardly and outwardly, the lower end of said take-off arm being arranged for movement around the coil of wire on the support in response to rotation of the take-off arm in the uncoiling operation and the passage of the wire therethrough, a coil spring at the lower end of the take-off arm arranged to be vibrated by the action of the wire thereon and thus to assist in loosening each convolution of the wire as it is uncoiled, and a retractable latch cooperating with said spindle to prevent vertical movement of the spindle on said support during the uncoiling operation.

7. In a wire uncoiling apparatus a support for a loosely wound coil of wire, a rotatable take-off arm having an outlet end and an inlet end movable around the coil of wire, the inlet end of said take-off arm being freely movable relatively to the outlet end widthwise of the coil in the uncoiling operation to accommodate the arm to varying widths and eccentricities of the convolutions of wire in the coil.

8. In a wire uncoiling apparatus a support for a loosely wound coil of wire, a tubular take-off arm mounted to rotate about an axis substantially central of a coil of wire on the support, the intake end of the take-off arm being arranged to move around the coil of wire in response to the rotation of the take-off arm in the uncoiling operation, and means connecting the inlet end portion of the take-off arm to the outlet end portion for movement relatively thereto in any direction transversely of the wire.

9. In a wire uncoiling apparatus a support for a loosely wound coil of wire, a rotatable take-off arm having an outlet end and an inlet end movable around the coil of wire, said take-off arm having a flexible, resilient portion connecting the inlet and outlet end portions of the arm and permitting the inlet end portion to move relatively to the outlet end portion in all directions transversely of the entering wire during the uncoiling operation.

10. In a wire uncoiling apparatus a support for a loosely wound coil of wire, a rotatable take-off arm having an outlet end and an inlet end movable around the coil of wire, and a coil spring adjacent to the inlet end and connecting the inlet end to the rest of the take-off arm for movement relatively thereto in any direction transversely of the wire as it enters the inlet end.

11. Uncoiling apparatus of the character de-

scribed including, in combination, a normally fixed reel for supporting coil wire, a fixed spindle disposed axially of the reel, a revoluble support journaled on the spindle, a guide tube secured to said support comprising an axial wire delivering portion and an outer wire receiving portion, and a wire guide ring flexibly secured to the receiving portion of said tube.

12. Uncoiling apparatus of the character described including, in combination, a normally fixed reel for supporting coiled wire, a fixed spindle disposed axially of the reel, a revoluble support journaled on the spindle, a guide tube secured to said support comprising an axial wire delivering portion and an outer wire receiving portion, a spring secured to said receiving portion, and a guide ring secured to the spring at a point remote from its point of attachment to the tube.

13. Uncoiling apparatus of the character described including, in combination, a normally fixed reel for supporting coiled wire, a fixed spindle disposed axially of the reel, a support rotatably mounted on said spindle, a guide tube secured to said support and having a wire delivering portion disposed in substantial alignment with the axis of the guide spindle, said tube having an outer wire receiving portion whose extremity extends circumferentially in juxtaposition to the periphery of the coil of wire supported by said reel, the wire receiving portion of the tube having a flexible tension member secured thereto, and a ring secured to said member and adapted to exert a gentle tension on the wire being uncoiled from said reel as a result of the flexing of said tension member.

14. Uncoiling apparatus of the character described including, in combination, a normally fixed reel for supporting coiled wire, a fixed spindle disposed axially of the reel, a revoluble support journaled on the spindle, a guide tube secured to said support comprising an axial wire delivering portion and an outer wire receiving portion, said receiving end of the tube having a helically coiled spring secured thereto, and a ring secured to the end of the spring remote from the tube, said ring being adapted to exert a gentle tension on the wire being uncoiled as a result of the rotary movement of the tube coupled with the flexing of the spring.

CHARLES R. ROHWEDER.
